UNITED STATES PATENT OFFICE.

RUFUS W. BAILEY, OF KANSAS CITY, MISSOURI.

ENGINE.

Application filed July 6, 1925. Serial No. 41,535.

This invention relates to door engines, and with regard to certain more specific features to air engines for operating door closing and opening devices of the oscillating, sliding or 5 folding type.

Among the several objects of the invention may be noted the provision of an oscillating engine which requires no linkage for converting reciprocating into oscillating motion 10 such as is required for operating doors; the provision of an engine which eliminates side thrust on the cylinder walls and produces a constant torque throughout its stroke; and the provision of an engine which is simple in 15 construction and free from inherent leakage factors and is economical of operation and manufacture. Other objects will be in part obvious and in part pointed out hereinafter.

The invention accordingly comprises the 20 features of construction, combination of elements, and arrangements of parts which are exemplified in the structure hereinafter described, and the scope of the application of which will be indicated in the following 25 claim.

In the accompanying drawings, in which is shown one of various possible embodiments of the invention,

Fig. 1 is a plan view of the engine shown in 30 full stroke position;

Fig. 2 is a vertical section taken on the line 2—2 of Fig. 1;

Fig. 3 is a fragmentary enlarged section of the piston;

Fig. 4 is a fragmentary enlarged section of the inlet and cushioning exhaust valve;

Fig. 5 shows an application of compound engines to a door opening linkage;

Fig. 6 is a plan view of Fig. 5; and

Fig. 7 is an elevation showing two of the 40 improved engines compounded on a single shaft.

Similar reference characters indicate corresponding parts throughout the several 45 views of the drawings.

Referring now more particularly to Fig. 1, there is illustrated at 1 a circularly cored casing or cover, adapted by means of flanges 3 to be fastened to a frame work or appurtenance near a door or set of doors.

Passing through the center of the circular bore is a drive shaft 5 which is mounted in a bearing 6 of a boss 8 (Fig. 2). The bearing is of the radial-thrust type and will resist either side or uni-directional end thrusts. 55 It may be constructed to take end thrusts in

two directions, if desired. There is provided no cover on the opposite side of the casing, in this embodiment of the invention.

Clamped horizontally to the shaft 5 is a 60 segmental cylinder block 7 adapted to swing with the drive shaft 5 within the circular core of the casing. A split clamp 9 holds the block tightly to the shaft. The clamp is formed integrally with the block 7.

The block 7 is torically bored at 11. The bore 11 forms a curved cylinder having its horizontal center line concentrically curved about the axis of shaft 5. To one end of the cylinder is screwed an air tight head plate 13. To the other end is screwed an annular tail plate 15 having an inner annular lip 17 formed thereon, which lip extends into the curved bore 11 for purposes to be described.

Beside the movable cylinder block 7 and its accompanying parts, the core of casing 1 carries a stationary hollow gooseneck piston rod 19. The gooseneck rod 19 is made hollow by means of a cored passage 21 passing therethrough.

At one end of the rod (Fig. 3) the passage 21 is met by a substantially tangential tapped hole 23. This hole 23 has screwed therein a bored nipple 25 which is provided with a hexagonal shoulder 27. The end of the gooseneck rod 19 is faced in a substantially radial manner with respect to the casing 1. The nipple 25, when screwed into the hole 23 holds a round leather gasket 29 against the face of rod 19, of a diameter equal to the diameter of cylinder 11. It holds clamped between its shoulder and the gasket a metallic washer 31 of lesser diameter than the cylinder, a leather piston 33 and a spacer collar 35. The piston 33 is equal in diameter to the bore of the cylinder 11 and is provided with an annular sealing lip 37. The spacer collar 35 is provided, in order that a wrench may be applied to the shoulder 27 without mutilating the lip 37 of the piston 33.

As stated the gooseneck rod does not move, and neither does the piston thereon. At a distance of substantially 180 degrees from the said piston 33, along the gooseneck, is formed a hollow boss 39. The boss 39 is an integral part of the gooseneck. The boss 39 is provided with a short, hollow extension 41 adapted to snugly fit a hole in the casing 1. The gooseneck is held in position in the casing, by means of studs 43 passing through the casing and into said boss.

An air pipe 45 leads to the hollow passage

47 of boss 39. The passage 47 is increased in size at its upper end 49 and is provided with a centrally located beveled valve seat 51.

Fig. 4 shows a detail of the check valve for 5 the passage of boss 39.

The valve comprises a bored stem 53 provided with ribs 55. The outside of the ribs are adapted to fit the lower bore 47 and ordinarily permit passage of air between the stem 10 53 and the wall of bore 47. A beveled hollow shoulder 57, forming an integral portion of the stem 53, and continuing the said bore, seats its outside beveled portion on the said valve seat 51 to form a seal. The shoulder 57 15 is threaded outwardly and receives thereon an inverted-cup shaped cap 59. The outside diameter of the cap is less than the inside diameter of the passage 49 and will permit ample passage of air through passage 49. The 20 screw connection between the cap and the shoulder is of a tight fit in order that the cap may be adjusted to various positions on the shoulder and hold any given adjustment.

Radially bored into the cup (from outside 25 to inside) are holes 61. These holes are helically arranged on the side of the cup, or may be staggered. The top of the cap is closed. Hence as the cap 59 is screwed down on the shoulder 57 to different positions, various 30 numbers of holes 61 are free to permit passage of fluid to the interior of the cup or vice versa. The cap provides adjustable means whereby predetermined desired amounts of air may be permitted to flow through the bore 35 of the stem 53 and shoulder 57.

The upper bore 49 is provided with an air tight plug 63 (Fig. 2). A spring 65 reacts between this plug and the top of the inverted cup 59 to normally hold the check valve assembly to its valve seat 51.

The passage 21 of the gooseneck rod 19 communicates with the upper bore 49. This passage 21 also communicates with the inside of the curved cylindrical bore 11 in the following manner:

The boss 39 is bolted to the casing at one side of the bottom thereof as described. The gooseneck, integral with the boss, passes around the centrally mounted shaft 5 in an 50 arcuate fashion, clearing the path of movement of the clamp 9.

At a point substantially 180 degrees from the said boss 39, is formed on the gooseneck 19 the piston 33. The description of the fastening for the piston has been given herein.

The piston is adapted to slidingly fit the cylinder 11. At the tail end of the cylinder, behind the piston is mounted the said annular plate 15 which carries the annular lip 17. 60 The lip 17 cooperates with the gasket 29 when the tail end of the cylinder is at the rear of the piston and hence prevents leakage of air at full stroke of the engine (Fig. 1). The lip clears the gooseneck at all stroke positions.

65 It should be understood that the cylinder

casting can move from its Fig. 1, full stroke position, counter-clockwise through an angle of approximately 90 degrees, to its zero-stroke position. The cylinder block, of course, moves the drive shaft 5 with it. The particular angle employed for the cylinder swing is not limited to 90 degrees.

A stop 67, bolted to the case 1 prevents the head plate 13 from striking the piston in zero-stroke position of the cylinder. The stop 67 75 cooperates with the tail plate 15 at zero-stroke.

The operation of the engine is as follows: Assume the cylinder to be in its zero-stroke 80 position.

A valve V in the air line 45 (in dotted lines) is opened and air under pressure passes to the pipe 45 and into the passage 47. The check valve is lifted from its seat by the pressure of the air. Some of said air passes through the bore of the valve, into the cup 59 and out of the holes 61, but most of it passes between the bore 47 and stem 53, past the bevel 51 and between the cup 59 and bore 49. All of it goes through the passage 21, nipple 25 and into the cylinder 11. The reaction of the air on the cylinder head 13 causes the cylinder block 7 to take its full stroke position as shown in Fig. 1. This action of the block 7 rotates the shaft 5 clockwise (Fig. 1) to operate a door opening mechanism, say, to door-open position. The lip 17 seats on the relatively soft gasket 29 to form an air tight seal against air escaping from the cylinder while the engine is in full stroke position. Since 100 the engine is in full stroke position a relatively long period of time for a given cycle, the saving in leakage air is pronounced.

In order to return the shaft to its original position, it is only necessary to turn the said 105 external valve in the line 45, in such a way that the pressure in said line is relieved, that is, turn the valve to exhaust position from its inlet position. The type of valve required for such action is the common three-way 110 valve.

A conventional spring-return mechanism may be employed on the shaft 5 which is, of course, inoperable when air is in the cylinder as described.

When air pressure is relieved in the line 115 45, the tendency for the shaft 5 and the block 7 to return to their original positions causes air to exhaust from the cylinder 11 through the nipple 25 and the passage 21 of the stationary gooseneck rod.

The exhausting air, with the aid of spring 65 seats the check valve. Hence air can not rush out past the beveled seat so quickly and must more slowly pass through the constricted openings formed by the holes 61. It then passes through the bore of the check valve to the line 45 and exhaust.

The purpose of constricting the passages upon exhausting the engine, is to prevent a 130

quick and violent closing action of doors linked to the engine shaft and the spring return.

Two of these engines may be compounded 5 on a single drive shaft, one operating clockwise and the other counter-clockwise. Each engine upon going to full stroke position, to 10 operate a door opening linkage, causes the other to exhaust, that is, go to zero stroke position. The engines are timed to bring about the above result. The timing merely involves turning one engine upside down and putting it back to back with a like engine. The result shown in Fig. 7 is then obtained 15 where the solid line cylinder is in full stroke position and about to be returned by the dotted line cylinder which is in zero-stroke position. When two engines are timed as described it is necessary to have the valves V 20 which feed them synchronized by a suitable mechanism such that when one turns to air feeding position the other turns to exhaust and vice versa. A suitable linkage which might be used to synchronize two valves V¹ 25 and V² for compound engines is shown diagrammatically in Fig. 5. The valve V¹ can be assumed to be in inlet position while the valve V² is in exhaust position.

The application of compound engines to a 30 particular door mechanism is illustrated in Figs. 5 and 6. The illustration will serve to show the operation of a single spring-returned engine also.

The engine or engines are connected with 35 the drive shaft 5 as described and are adapted to oscillate the shaft through approximately 90 degrees.

The shaft 5 is mounted in bearings 69 and carries fast thereto a pair of bevel gears 71. 40 The gears 71 mesh with similar gears 73 on vertical shafts 75. The gear ratio is 1:1 in each case. However one of the vertical shafts 75 is driven clockwise and the other counter-clockwise. This is arranged by properly 45 placing the bevel gears 71.

Each of the vertical shafts 75 carry a door leaf 77 and each of the leaves 77 have hinged thereto another leaf 79. The leaves 79 are provided with downwardly extending pins 81 50 extending into lateral guide slots 83 in the floor under the doors.

Operation of a simple or compound engine

on the shaft 5 will turn it through 90 degrees from its Fig. 5 position. The vertical shafts 75 will turn 90 degrees and throw the leaves 55 into their Fig. 6 position, that is, open the doors. The doors may be closed by means of the return spring on the simple engine, when air is exhausted, or by the return action of one of the then stroking compound engines. 60 The pins 81 slide along the grooves 83. In either case an action of one or more of the external three way valves is required for exhausting purposes.

The engine or engines might be mounted 65 directly on one of the shafts 75 with the same result. Many other door linkages are adaptable to be operated by this engine, the one herein shown serving illustrative purposes. The engine may also be used for other purposes where oscillating movement is required. 70

From the above it will be seen that the several objects of the invention are attained and other advantageous results achieved.

As many modifications of the embodiments 75 above illustrated might be made without departing from the spirit or scope of the present invention, it is intended that the above description and accompanying drawings and claim shall be interpreted as illustrative 80 and not in a limiting sense.

I claim:

An oscillating engine comprising a drive shaft, a movable curved cylinder thereon and a stationary piston cooperating with the cylinder, a passage leading to and through said passage to operate the cylinder to stroke, means for automatically returning the cylinder and means for permitting relatively slow reverse passage of fluid as the cylinder returns, said last named means comprising a hollow shouldered stem arranged in spaced relationship to a bore, a seat for the shoulder in said bore, a cap screwed to the stem above the shoulder and arranged in spaced relationship to the bore and holes in said cap communicating with the hollow stem, said holes being adapted to be covered or uncovered by adjusting the threaded cap. 90

In testimony whereof, I have signed my 100 name to this specification this 30th day of June, 1925.

RUFUS W. BAILEY.
